UNITED STATES PATENT OFFICE.

THOMAS J. GAFFNEY, OF ALBANY, NEW YORK.

AUTOMOBILE-SIGNAL.

1,299,166.

Specification of Letters Patent. Patented Apr. 1, 1919.

Application filed October 31, 1917. Serial No. 199,490.

To all whom it may concern:

Be it known that I, THOMAS J. GAFFNEY, a citizen of the United States, residing at Albany, in the county of Albany, State of New York, have invented certain new and useful Improvements in Automobile-Signals; and I do hereby declare the following to be a full, clear, and exact description of the invention, such as will enable others skilled in the art to which it appertains to make and use the same.

This invention relates to direction indicators for use by automobilists.

The object of this invention is to provide a practical device which may be used by drivers of automobiles to indicate to following drivers, the intention with reference to changes of direction or speed which should be communicated for the guidance of the following drivers. More particularly, it is the object of this invention to provide an indicator blade which may be lifted by the driver from a suitable hook or other support which is conveniently located and either projected from the side of the car while held in the hand or else stuck upon the door or edge of the car body to indicate to following drivers the signaling drivers' intentions. Following the usual practice, drivers customarily project the arm from the side of the car to indicate a purpose, and in rainy weather, when signaling is particularly necessary, the drivers' sleeves and arms are soaked with rain. This is particularly disagreeable to ladies in social dress or shopping costume, and may be wholly avoided by the use of the device of the present invention.

With the above objects in view, and such others relating to the details of construction, as may hereinafter appear, my invention will now be fully set forth and described, reference being had to the accompanying drawings.

45 In the drawings:—

Figure 1 is a perspective view of a portion of a front compartment of a car body showing the use of my invention.

Fig. 2 is an enlarged elevation,

50 Fig. 3 is another elevation showing a different position of the device, and

Fig. 4 is a vertical section therethrough.

Referring more particularly to the drawings, 1 represents an indicator body, which, while preferably formed of sheet metal, with equal adaptability, may be constructed of

wood or other metal. The blade is cut into the form of an outstretched hand, which projects from a sleeve 2. The sleeve 2 provides a background against which a designating plate 3 may be positioned, the latter preferably being hinged to the edge of the portion 2.

As above stated, the device is preferably formed of sheet metal, and when so constructed, has its edges reinforced by means of a wire binding 4 which is crimped into the overturned top, bottom and rear edge of the portion 2. At the rear of the portion 2, midway between the top, and bottom edges, the wire binding 4 is turned outwardly and twisted to provide a shank 5. In the twisting operation, however, the shank 5 is interrupted by the formation of upper and lower pairs of parallel clamping arms 6 which are spaced such a distance apart that they may be engaged over the top edge of the car body or the door to hold the indicator in outstretched horizontal relation, a pair of oppositely projecting clips being 75 thus provided on the shank 5. It may be necessary, for the protection of the car body, to cover the clamping arms with rubber or other coverings 7, though this is not an essential characteristic of the device. The shank 80 5, at its rear end, is continued in the looped hand grip 8, and the latter, in turn, may terminate in a loop 9 for engagement over a suitable hook or other support.

I prefer to hinge, over the sleeve portion 90 2 the plate 3, which has indicated upon one side the word "Left" and upon the other side the word "Right". I secure the plate 3 to the portion 2 by cutting away the metal of the latter along one of its edges as at 4', 95 so as to free the corresponding extent of the wire binding. The exposed portion of the binding provides a hinge pintle upon which one edge of the plate 3 may be pivoted, in such relation that it may be thrown against one side or the other of the portion 2. The arrangement of the words is such that when the plate 3 is swung against one side of the portion 2 the indicator will read "Slow left". In this position, probably, the hinge portion of the plate 3 will be at the bottom, and a spring wire clip 10 carried by the portion 2 will be employed to hold the parts in that relation. Furthermore, that may be considered the normal condition of adjustment 100 of the parts, and when it is necessary to indicate "Slow right". The clip 10 is released

so that the plate 3 may drop away from the portion 2 and may be swung into position against the opposite side of the device upon the reversal of the latter, thereby combining 5 the word "Right" with the word "Slow" in indicating relation. Since the release of the device from its locked "Left" position for turning into the "Right" position can be almost instantly effected, whereas the operation 10 of locking the device in its "Left" position cannot be so quickly effected. It was stated above that the normal position of the device would probably be preferably considered as that in which the plate 3 is locked 15 in the "Slow left" indicating position.

It will be apparent from the foregoing description that I have provided a practical device for use in automobiles for acquainting the following drivers with the intentions 20 of the signaling driver with a minimum of effort and inconvenience, especially in stormy weather. Furthermore the device is an inexpensive article of manufacture, and requires no special mechanism for mounting 25 or operation, since it is merely a device for manual employment.

What I claim as my invention is:—

1. An indicating device for automobiles comprising a signal plate, a grip hand extending from one end of the signal plate whereby said plate may be manually wielded, 30

and clip portions carried by the handle and adapted to embrace the edge of an automobile body to detachably secure the device thereon.

35

2. An automobile indicator comprising, a sheet metal signal plate, a wire binding member for edge portions of the plate, a portion of said wire member being bent to form a grip handle extending from one end 40 of the plate, and said wire member being further bent to form clip arms engageable over the edge of an automobile body for detachably securing the device thereon.

45

3. An indicating device for automobiles, comprising in combination, a plate to be manually extended from the side of the car, said plate being shaped as a direction signal, a handle extending rearwardly from the plate, means for engaging the device over 50 the edge of an automobile body, and a second plate hinged to the first plate to be swung from one side to the other, and bearing selective indicia upon its opposite sides for exposure when the device is extended from the 55 side of a car.

In testimony whereof, I affix my signature in the presence of two witnesses.

THOMAS J. GAFFNEY.
